FRED D. WILSON, OF HARVEY, ILLINOIS, ASSIGNOR TO AUSTIN MANUFACTURING CO.,
OF CHICAGO, ILLINOIS, A CORPORATION OF ILLINOIS

FOUR WHEEL DRIVE ROAD MACHINE

Application filed October 20, 1928. Serial No. 313,730.

This invention relates to road machines and more in particular to a motor grader propelled by its own power and provided with a four wheel or dual drive.

5 The primary function of the ordinary road machine or motor grader to properly maintain the surface of macadam or gravel roads, and since the great majority of such macadam and gravel roads are provided with a 10 relatively hard surface, great pressure on the surface tool or blade is necessary and such pressure can only be obtained by borrowing weight from the frame and associated parts through the medium of the blade 15 or tool controlling mechanism. In other words, in order to push the blade into the roadway, the frame must be pushed upward, and because the frame of the ordinary type of road machine or motor grader is rigidly 20 secured to a tractor, the weight borrowed for use at the blade or surfacing tool is taken from the traction wheels of the tractor. This not only reduces the traction or pushing ability of the traction wheels by causing slippage 25 on the ground surface, but also causes rapid wear of the tires which are generally made of rubber and are quite expensive.

Furthermore, in the common type motor grader with a single pair of driving wheels 30 at the rear, it is obviously easier for the blade, when positioned diagonally relative to the line of travel and heavily engaged in moving material sidewise, to pull the entire machine off the desired course; i. e. a heavy side load 35 on the blade will cause the front steering wheels to skid towards the ditch when material is moved in the opposite direction much easier than in a machine having four driving wheels as set out in the present invention, 40 for the reason that the front steering wheels are entirely unassisted by the single rear pair of driving wheels insofar as holding their course is concerned.

In my improved motor grader, the fact 45 that four driving wheels are employed and are non-steerable relative to each other, means that the natural tendency of the machine as a whole is to follow a straight course and to be deflected only by the front steering wheels 50 when steered in the conventional manner by

the operator and not be whipped and pushed sideways by material acting against the face of the blade or moldboard. My present construction as a whole, makes the changing of the direction of travel more difficult, in that 55 the steering wheels have more work to do when turning a corner, than on a conventional machine because of the fact that to change the course of travel of the machine, certain of the four driving wheels must skid slightly on 60 the road surface. This feature in a motor grader is an advantageous one for the reasons heretofore given, since it is obvious that while it is entirely possible for the front wheels, 65 because of the leverage gained by the long frame and their position at the forward end of it, to cause the necessary skidding of the rear wheels to make a turn, the blade is not positioned so as to have the same leverage, 70 however, and therefore it will withstand a much greater side pressure of material against its face before changing the course of the machine or before it is overloaded, 75 than is possible with the ordinary two wheel drive motor grader.

The location and arrangement of my four driving wheels taken in connection with the method of connecting the tractor and grader frame, lends further stability to the machine while at work in that on the ordinary motor grader the entire tractor weight is carried 80 on the single pair of drive wheels which are located at the extreme rear of the long frame and are generally a greater distance from 85 the blade than are the front pair of driving wheels on my present invention.

In my invention, the tractor weight is on four wheels, which are all drivers and all assist in propelling the machine, the wheels being arranged in tandem relation, allowing 90 approximately sixty-five percent of the tractor weight to be carried on the front pair of wheels. The front pair of drive wheels in the present construction are unaffected by any pressure applied to the blade since the 95 tractor or power plant is pivoted to the grader frame at its rear axle housing and not made rigid as in the ordinary type of grader. This construction permits the front end of the power plant to be always free 100

and unhampered regardless of the kind of work done by the blade or the amount of pressure applied thereon. It thus follows that when a portion of the frame weight is borrowed as when applied to the blade for heavy work, the tractive effort of the rear pair of wheels only is effected and since each front wheel is driven from its respective rear wheel and is constantly connected to it by transmission means, the objectionable skidding and slipping of the rear wheels is prevented by the weight on the front drive wheels, the tractive effort of which is always constant. The front end of the power plant, instead of being carried by the frame of the grader, as on all previous machines, is carried on its own drive wheels and axle, which in turn are pivotally connected by heavy rocker beams with the rear axle. The term power plant as used in the specification and claims is meant to include an engine or other prime mover and the driving and supporting means therefor.

The present construction allows the front end of the power plant to oscillate freely up and down inside the grader frame as no part of its weight is carried by the frame, and it has no connection with the frame other than a simple adjusting device to keep it in place between the side rails without touching either of them. While the front end of the power plant is free to rise and fall on the forward drive wheels, due to any unevenness of the ground, this motion is not communicated to the grader, as there is no connection between the tractor and the grader except through the rear axle to which the side rails are attached as on all other machines. The entire weight of the power plant is placed on its own four wheels, and then part of the tractor weight which on other machines is carried to the grader frame on the front carrying wheels, is now placed on the forward drive wheels, adding considerable extra traction to the power and efficiency of the machine.

Among the objects of my invention are to provide a road machine or motor grader having an elongated frame on the rear end of which is pivoted a four wheel drive mechanism, the front end being supported and steered by a conventional steerable two wheel truck; further to provide a road machine having four non-steerable driving wheels, two on each side of the frame and each front wheel being driven from its respective rear wheel; further to provide a road machine or motor grader having an elongated frame with a four wheel drive mechanism pivotally connected to the rear of the frame for vertical oscillation, and means connecting the front of the tractor mechanism to the frame of the grader, said means permitting relative vertical movement only; further to provide means for connecting the front and rear

axles of a tractor mechanism for permitting their relative movement to control the tension on a connecting drive chain; further to provide a spring cushioning means for supporting one end of the power plant.

My invention further provides an improved blade operating mechanism; further to provide a novel construction of maximum simplicity, efficiency, economy and ease of operation, and such further objects, advantages and capabilities as will later more fully appear.

My invention further resides in the combination, construction, and arrangement of parts illustrated in the accompanying drawings, and while I have shown therein a preferred embodiment, I desire it to be understood that the same is susceptible of modification and change, without departing from the spirit of my invention.

In the drawings:

Fig. 1 is a view in side elevation of my road machine, two of the driving wheels having been removed to more clearly disclose details of construction.

Fig. 2 is a top plan view of the road machine.

Fig. 3 is a view in vertical cross section taken on the line 3—3 of Fig. 1.

Fig. 4 is a fragmentary view of the supporting construction for the forward drive wheels.

Fig. 5 is a view in vertical cross section taken on the line 5—5 of Fig. 2.

Fig. 6 is a view in vertical cross section on the line 6—6 of Fig. 2.

Fig. 7 is a top plan view of one of the blade operating mechanisms.

Fig. 8 is a view in vertical cross section taken on the line 8—8 of Fig. 7.

Referring more particularly to the drawings, my improved road machine comprises an elongated arch frame 1 provided with front steering wheels 2 mounted upon an axle 3 and rear traction and drive wheels 4 and 5. The drive wheels 4 are mounted on the drive shaft 6 of a power plant 7, while the forward drive wheels 5 are mounted on an axle 8, the ends of which axle are connected at each end by means of a heavy steel rocker beam 9 to the rear axle housing 10, thus keeping the front and rear drive wheels always in exact alinement. This axle 8 is further attached to the front end of the power plant by heavy multiple leaf springs 11 so that said power plant has a spring support on its own mounting and in addition is free to move up and down inside the frame of the grader as any inequalities in the road surface make such movement necessary, using the rear axle of the tractor or power plant itself as a pivotal point. The leaf springs 11 are mounted on the underside of the rocker beam 9 and are rigidly attached thereto by suitable anchoring bolts 12 and 13. A housing 14 is mounted

within the rocker arm 9 at its front end 15, this housing further providing a bearing surface for the forward axle. In order to properly drive the forward traction wheels, I 5 provide a sprocket 16 mounted on the hub 17 of the driving wheels 4, and a sprocket 18 on the hub 19 of the forward traction wheels 5. A roller bearing chain 20 engages the sprockets and drives the forward traction 10 wheels, thus providing a dual or four wheel drive for the machine. In order to allow for the vertical oscillation, the springs 11 are attached to and pivoted on rocker arms 21 attached by suitable bracket means 22 to the 15 frame member 23 at the forward end of the power plant.

In order to prevent side motion of the power plant relatively to the frame, I provide an 20 equalizing device comprising horizontal arms 24 and 25 pivotally connected at 26 and 27 to the frame 23. The member 24 is further pivoted at 28 to an arm 29, the member 25 being pivoted at 30 to the other end of this arm. A 25 diagonal brace rod 31, rigidly secured to the frame of the grader by brace members 31^a and 31^b, is provided with an extension or lug 32 providing a bearing for a pivot 33 for the arm 29.

The front wheels 2 are operated by a steering 30 shaft 34 and steering wheel 35. Located directly behind the front wheels and near the forward end of the machine, is a scarifier 36 mounted upon a frame 37, which frame is pivotally mounted at 38 to the forward part 35 of the machine. This pivotal connection allows for the scarifier to be raised or lowered from contacting relation with the ground. The mechanism for raising or lowering the scarifier comprises arm members 39 and 40 40 mounted on opposite sides of the machine and connected to the scarifier at its ends. The arm members 40 are operated by suitable gearing 41 mounted on the frame 1 of the machine, the gearing being operated by 45 means of a shaft 42 operated by a suitable steering wheel.

Located under the arched frame 1 is a triangular frame 43, the forward end 44 of which floats on a vertical pivot pin (not 50 shown). The construction of the forward end of the frame allows for a rotation thereof so as to permit the sides of the blade and frame to be raised and lowered by the operator at will. Rotatably mounted on the under 55 side of the frame 43 is a horizontal blade supporting wheel 45 carrying a grader blade 44^a, this wheel having a circumferential flange 45^a. In order to rotate the wheel 45, the inner periphery of this wheel is provided 60 with an arcuate rack *a* meshing with a spur gear (not shown) on a shaft *b*. This shaft at its upper end is provided with a bevel gear *c* meshing with a bevel gear *d* on a shaft *e*, rotated from the operators station by a hand 65 wheel *f*. A pair of pivotal connections 46

to which are attached vertically extending rods 47, are mounted on a cross arm 48 attached to the under side of the frame 43. These rods 47 are in turn attached at their upper ends to arms 48^a, which arms are pivotally connected to a shaft 49 extending transverse of the machine. 70

Each arm 48^a is attached to and made integral with a bell crank 50, and is bifurcated at its lower end for attachment with the rod 75 47. An arm 51 on the bell crank is pivotally attached at its upper end to a tubular shaped casting 52. This casting is provided at its rear end with a threaded portion 53, which threaded portion is adapted to engage the threaded end 54 of a shaft 55. A tube 56 is pressed into the main casting 52 to protect the threads and also to provide a support for a bearing 57 for the shaft 55. 80

The shaft 55 is reduced at its rearward portion and fits into a housing 59. A sleeve 60 surrounds the reduced end of the shaft within the housing and is provided with a shoulder 61 against which roller bearings 62 and 63 abut. These bearings fit intermediate 90 the sleeve 60 and the housing 59 and are there held in place. A closure 64 is attached to the open end of the housing, and provides an abutting surface for the outer wedge members of the roller bearings. A hand wheel 95 65 fits on the end of the shaft and is adapted to rotate the same. The sleeve 60, hand wheel 65, and the shaft 55, are all locked together by means of a nut 66 and revolve as a unit inside of the housing 59. The roller bearings take the end thrust in either direction. By revolving the hand wheel, the shaft 55 may be rotated in either direction, and this shaft through its threaded portion 100 engaging the threaded portion of the casting 52, will either draw this casting towards it, or force it away. By means of this operation, the bell crank is either raised or lowered and through its corresponding lever arm will 105 either raise or lower the blade assembly. The housing 59 is pivotally mounted at 67 for oscillation as required by the motion of the bell crank. A spring 68 is connected to the bell crank at 69 through a chain 70, the spring being attached at its other end at 71 110 to the frame 1.

In order to provide lateral adjustment of the frame 43 and blade crosswise of the road or transverse of the longitudinal axis of the machine, I provide a hand wheel 72 mounted 120 on an obliquely disposed shaft 73, which shaft is suitably journaled on the frame of the machine. This shaft is provided with a bevel gear 74 meshing with a bevel gear 75 mounted on a threaded shaft 76. The 125 threaded shaft 76 passes into and through a threaded block or nut 77, which is suitably attached to the rear or base of the triangular frame 43. Whenever the operator rotates wheel 72, he rotates the threaded shaft or 130

screw 76 and thus swings the frame and blade in a horizontal plane about the connection 44 at the front of the machine.

From the above detailed description, it will be seen that I have provided a road machine or motor grader of the greatest possible efficiency and rigidity. By means of the four wheel drive construction, it is possible to proceed over soft ground and get out of slippery, wet, or otherwise impossible holes 10 and keep its place on slippery roads without sliding sidewise or skidding into the ditch, in a manner totally foreign to the old two wheel type. The tractive effort of any motor grader is dependent upon the area of contact between the wheels and the ground and the pressure applied to that area. Naturally, the greater weight and traction of the four driving wheels of my construction, means 15 more and better ground contact, which being spread over four distinct areas separate from each other, so that if one or two wheels run into a soft or wet spot there will still be two or three left on hard ground, and these 20 provide traction enough to carry the machine to places where a two wheel tractor would stall and have to be dug or towed out. Also the forward drive wheels pressing down the softer material as it passes through, provides 25 a solid footing for the rear wheels following immediately after. This creates an ability to work on soft ground and under unfavorable conditions. An important advantage is that by locating the driving 30 wheels at the rear of the machine with one pair of the driving wheels spaced forwardly from the other pair and positioned a substantial amount nearer to but behind the grader blade than the other pair, an effective 35 means is provided which offers a substantial resistance to the tendency of the side draft to force the machine out of its normal course. 40

Further, the distribution of weight on four wheels instead of two, even though total weight is greater, means a less down pressure 45 per wheel and a corresponding lessening of the tendency to get stuck in soft places, which makes it possible to get out on the road sooner after a storm or earlier in the 50 spring than with any of the two wheeled machines.

By virtue of the four wheel drive construction, the four wheels become positive drive wheels, each one taking its portion of the 55 traction load. This gives positive tractive effort on four separate and distinct parts of the road surface, eliminating any chance of the machine being mired down by running into a hole or soft place. The freedom of 60 motion that the tractor has in the grader frame enables it to adapt itself easily to whatever type of road it may be passing over, and the drive wheels on either side can pass over obstructions without deflecting the 65 course of the grader as a whole.

Having thus disclosed my invention, I claim:

1. In a self propelled road grader, in combination a grader blade, an elongated frame on which the blade is adjustably mounted, 70 steering wheels supporting the front portion of said frame in front of the blade, a power plant connected to said frame in a position behind the blade, a pair of ground-engaging drive wheels driven from said power plant 75 and positioned adjacent the rear end of the power plant, and a second pair of ground-engaging drive wheels also driven from said power plant, said second pair of drive wheels being spaced forwardly from the first pair 80 and positioned a substantial amount nearer to the grader blade than the first pair but behind it, so as to provide additional traction, and also providing a substantial resistance to the tendency of the side draft to force the machine out of its normal course. 85

2. In a self propelled road grader, in combination a grader blade, an elongated frame on which said grader blade is adjustably mounted, rotatable means for supporting and steering the front end of the frame and positioned in advance of the grader blade, a power plant in the rear portion of the frame and so connected therewith as to prevent any lateral movement of the power plant with 90 relation to the frame, a pair of ground-engaging drive wheels positioned adjacent the rear end of the frame and driven from the power plant, a second pair of ground-engaging drive wheels driven from said power plant and positioned in front of the first pair between the rear end of the frame and the grader blade, said two pairs of drive wheels being so spaced with relation to the 95 grader blade as to be effective to prevent lateral skidding of the road grader from a heavy side load on the face of the grader blade. 100

3. In a self propelled road grader, in combination a frame including a pair of elongated side members, rotatable supporting and steering means adjacent the front end of said frame, a grader blade adjustably mounted on said frame in the rear of said supporting and steering means, a power plant between the rear end portions of said side members and held against lateral movement with relation to said side members, a pair of ground-engaging drive wheels positioned adjacent the rear end of the power plant and driven from the power plant, a second pair of ground-engaging drive wheels driven from the power plant and spaced forwardly from said first pair, said second pair of drive wheels being 110 positioned between the rear end of the frame and the grader blade to effect additional resistance against lateral movement of the road grader from a heavy side load on the face of the grader blade. 115

4. In a self propelled road grader, in combination an elongated frame, rotatable supporting and steering means adjacent the front end of said frame, a grader blade adjustably mounted on said frame in the rear of said supporting and steering means, a power plant in said frame behind the grader blade so that one end of said power plant moves vertically within said frame but is held against lateral movement with relation thereto, a pair of ground-engaging drive wheels adjacent the rear end of the power plant and driven from the power plant, a second pair of ground-engaging drive wheels driven from the power plant and positioned between the first mentioned pair of drive wheels and the grader blade to effect resistance against lateral movement of the road grader from a heavy side load on the face of the grader blade.
5. In a self propelled road grader, in combination an elongated frame, rotatable supporting and steering means adjacent the front end of the frame, a grader blade adjustably carried by the frame rearwardly of the supporting and steering means, a power plant pivotally connected to the frame to the rear of the grader blade, a pair of ground-engaging drive wheels supporting the rear end of the power plant and driven therefrom, the front end of the power plant being vertically movable in the frame but held against lateral movement with relation thereto, a second pair of ground-engaging drive wheels driven from the power plant and positioned between said first mentioned pair of drive wheels and the grader blade for supporting the front end of the power plant and effecting resistance against lateral movement of the road grader from a heavy side load on the face of the grader blade, said second pair of drive wheels moving up and down with the forward end of the power plant and acting at all times as propelling units regardless of the condition of the road bed.
6. In a self propelled road grader, in combination an elongated frame, supporting and steering means adjacent the front end of the frame, a grader blade adjustably mounted on the frame rearwardly of the supporting and steering means, a power plant, a pair of ground-engaging drive wheels supporting the rear portion of the power plant and a pair of ground-engaging drive wheels supporting the forward portion of the power plant, both pairs of said drive wheels being driven from the power plant, the frame adjacent its rear end being pivotally connected with the power plant so that the latter may have an oscillatory movement with relation to the frame, the power plant being held at all times against lateral movement with respect to the frame, at least one pair of said drive wheels being in tractive engagement with the ground at all times whereby a force tending to raise the grader blade, frame and portion of the power
- plant does not affect the driving or traction engagement with the ground of at least one pair of drive wheels.
7. A road machine provided with a grader blade, a frame provided with side members carrying said blade, steering wheels at the front of said frame and driving wheels at the rear thereof, a power plant so mounted intermediate said side members that said power plant may oscillate vertically within said frame, and additional non-steerable driving wheels adapted to carry the front of the power plant and provide additional traction units whereby certain of said drive wheels give tractive effort regardless of the condition of the road bed, and prevent the frame from being whipped sideways and pulling the machine off the desired course due to a heavy side load on the face of the grader blade.
- In witness whereof, I hereunto subscribe my name to this specification.
- FRED D. WILSON.
